Attorney.

UNITED STATES PATENT OFFICE.

FREDERICK OATLEY BYNOE, OF TWICKENHAM, ENGLAND.

SUPERHEATER FOR AIR, VAPOR, OR GAS.

1,298,883.

Specification of Letters Patent.

Patented Apr. 1, 1919.

Application filed July 1, 1918. Serial No. 242,830.

To all whom it may concern:

Be it known that I, FREDERICK OATLEY BYNOE, a subject of the King of Great Britain and Ireland, and resident of Twickenham, county of Middlesex, England, have invented a new and useful Improvement in and Connected with Superheaters for Air, Vapor, or Gas, of which the following is a specification.

10 The object of my invention is to obtain a large volume of superheated (high temperature) air, vapor or gas by means of the hereinafter described construction of a superheater, an essential feature of the invention being the constant velocity of the air or the like maintained in passing through the heating chambers, means being provided to facilitate the cleaning of the air passages, and at the same time simplify the removal 20 or repair of the parts of the apparatus.

A superheater in accordance with my invention comprises:

1. One or any number of superimposed or otherwise arranged air, vapor or gas heating 25 chambers constructed of metal, clay, or any suitable refractory material, around which flow the hot gases from a furnace. Each chamber is closed at one end, and, in the case of several being employed, they are connected by a passage or passages between them at their open ends. The chambers are 30 oblong, rectangular or wedge-shaped, and, in the case of several being employed, they increase in cross-sectional area as they approach nearer the hottest gases from the furnace. The walls of the furnace may form one wall of the chamber nearest to it. The 35 external walls of these chambers form tortuous flue passages between the furnace and the chimney. The chambers are either horizontal, vertical, inclined, staggered, or placed side by side.

2. A sliding diaphragm of any suitable material dividing each heating chamber longitudinally into two wedge-shaped parts or compartments, except for a space at the closed end of the chamber, which space provides a passage from one compartment to the other for the air, vapor or gas which is 50 to be heated. The diaphragm may or may not be corrugated to allow for the expansion of the material of which it is made. The diaphragm is supported in position by side ledges or grooves, or other supports are

placed underneath at any position where 55 they may be required.

3. A head and box end to the diaphragm plate is provided for the purpose of making a tight joint in the outer wall of the connecting air passages or for the withdrawal 60 of the diaphragm for cleaning or renewal of parts.

For a clear understanding of the invention, reference is to be had to the following description and accompanying sheets of 65 drawings, in which:—

Figure 1 is a longitudinal section of an air superheater composed of four layers of heater chambers arranged in opposite series.

Fig. 2 is an end view thereof, partly 70 broken away in order to show the box to which the diaphragm is attached and the transverse position of the diaphragm in the heater chamber.

Fig. 3 is a longitudinal sectional view of 75 one of the superheater units, drawn to a larger scale.

Fig. 4 is a longitudinal section of a wedge-shaped heater chamber.

Fig. 5 is a perspective view of an alterna- 80 tive wedge-shaped heater chamber.

Fig. 6 is a plan view of the heater chamber shown in Fig. 5.

Like letters of reference indicate corresponding parts in the several figures. 85

In carrying out the invention and referring to Figs. 1 and 2, each heating chamber *a* is of oblong or rectangular shape, closed at the end *b*, but open at the end *c*, *c'*, and a sliding diaphragm *d* carried by a head *e* 90 extends along the interior of the chamber *a*, said diaphragm *d*, which is arranged at a slant and extends across said chamber and rests on side ledges *f*, dividing said chamber *a* into two parts or compartments *g* and *h*, 95 except for the space at *i* which forms a passage between said parts or compartments *g* and *h*; the diaphragm *d*, further, extends across and divides a passage, with which the open end *c*, *c'* communicates, into two parts *j* and *k*, *j* being the inlet and *k* the outlet for the air which is to be heated.

The head *e* of the diaphragm *d* is secured by a button piece *m* and lugs *n* to a box *o* supported in a frame *p* built in the external 100 wall *r* of the passage *j*, *k*.

The slanting position of the diaphragm *d* in the chamber *a* provides one compartment

5 *g* gradually increasing in cross-sectional area from *c* to *c*², and a second compartment *h*, also gradually increasing in cross-sectional area from *c*³ to *c*⁴, the sectional area of both compartments at *c*² and *c*³ being equal.

10 The diaphragm *d* can be removed for the purpose of cleaning the chamber *a* or for the renewal of parts, by simply disengaging the button piece *m* from the lugs *n* and then withdrawing said button piece *m* and with it the head *e* and diaphragm *d*.

15 The air, vapor or gas which is to be heated enters by two passages *s* and *s'*, flows into the first heating chambers *a* by way of the compartments *g*, through the openings *i*, and along the compartments *h*, into the main passageway *t* which connects the outlet *k* of the chamber *a* with the inlet *j* of 20 the next chamber *a* in the series, and so on until it leaves the superheater at the combined outlet *v*, the heat from the furnace *w* traversing the flues *x* and exiting by way of passage *y*.

25 The object of the gradual increase of the sectional area of the chamber compartments from the air, vapor or gas inlet to outlet is to provide for the expansion resulting from the increased temperature which would produce a back pressure on the fan or blower supplying the air, vapor or gas, and also increase its velocity through the heating chambers.

30 In cases where it is desirable to increase the differentiation between the sectional area of the air inlet and outlet, the heating chamber is of wedge-shape as shown in Fig. 4.

35 Figs. 5 and 6 represent an alternative method of obtaining the gradual increase in the cross-sectional areas between the inlet and outlet of the heating chambers, in which two reversely wedge-shaped members or boxes, of which Fig. 5 is a perspective view 40 and Fig. 6 a plan view, are combined. The two sections *a*, *a'* and *a*² and *a*³ open into one another so as to form one chamber *a*, *a'*, *a*², *a*³. A diaphragm *d*—Fig. 5—is introduced into that part of the chamber which 45 has the largest open end, and divides the whole chamber into two reverse wedge-shaped compartments except for a space at the closed end *a* which provides a passage similar to passage *i* Fig. 3 for the air, vapor or gas from the inlet *j* to one outlet *k*, viz.—*j* and *k* of the previous examples.

50 The same arrangement of connecting passages, and the same head and box end to diaphragm is applied as in the case of the use of an oblong or rectangular chamber shown in Fig. 1.

55 Each chamber in series has a larger sectional area than the one preceding it, so that the inlet of each chamber equals the outlet of the one before it. In this way the

increased expansion of the heated air, vapor or gas through all the chambers is provided for, and insures a constant velocity of the flow of the air from inlet to the superheater outlet.

70 The construction of the chambers provides for a comparatively thin column of air flowing in contact with a very large heating surface, and insures its being heated throughout to a high temperature.

75 Having now described my invention, what I claim as new and desire to secure by Letters Patent of the United States is:—

1. An air, vapor or gas superheater chamber characterized in that it is of oblong or 80 rectangular shape divided into two compartments by a removable sliding diaphragm placed at a slant to provide a passage of gradual increasing sectional area from inlet to outlet, substantially as described.

85 2. In an air, vapor or gas superheater, a diaphragm having a head and box end for the purpose of withdrawing the diaphragm and for making a tight joint in the outer wall of the inlet passage, substantially as 90 described.

95 3. In air, vapor or gas superheaters, a diaphragm, a box end thereto and means on said box end to hold said diaphragm in position, substantially as described.

100 4. A superheating furnace having opposite intake flue passages on each side of its heating compartment above the fire box, a plurality of superheating units arranged in opposing and alternating relation and having their open ends in communication with said intake flues, and means carried by the walls of the furnace constituting one side of the said intake flues, and projecting into the superheater units to divide the same into intake and discharge passages.

105 5. A superheating furnace having opposite intake flue passages on each side of its heating compartment above the fire box, a plurality of superheating units arranged in opposing and alternating relation and having their open ends in communication with said intake flues, and diaphragms carried by the walls of the furnace constituting one side of the intake flues, said diaphragms 110 projecting into the superheater units at an angle to divide the same into upper and lower communicating passages of gradually tapering width from the upper intake side of the diaphragm toward the lower opposite 115 side of the diaphragm.

120 6. A superheating furnace having opposite intake flues formed in opposite walls thereof, a plurality of superheater units closed at one end and having their free ends secured in the furnace structure and opening into said flues, the said superheater units being arranged in opposite superimposed relation within the heating chamber above the fire box of the furnace and being of gradu- 125 130

ally increasing size from the top of the heating chamber toward the bottom thereof, a removable diaphragm carried by the furnace structure for dividing the superheater units into passages of varying width.

5 7. A superheater unit for superheating furnaces consisting of a tubular body closed at one end and open at the other, and a diaphragm adapted to be disposed within 13 the chamber from the open end thereof to provide a double passage through the unit which passage is of gradually flaring width from the intake end toward the outlet end.

15 8. A superheater structure consisting of a furnace wall having a passage-way, a

superheater unit closed at one end and having its open end supported in said wall and opening into the passage, and a member removably fitted to the side of the wall opposite that carrying the superheater unit, 23 and adapted to obstruct the said passage to direct gases into the superheater unit and divide the latter into a double passage which increases in sectional area from the intake side of the diaphragm toward the outlet side 25 thereof.

In testimony whereof I have affixed my signature this 22nd day of May, 1918.

FREDERICK OATLEY BYNOE.
